Des. 220,687
Patented May 11, 1971

220,687

CAMPING AND UTILITY TRAILER

Nathan E. Spiese, East Petersburg, Pa., assignor to Wheel Mate Corporation, East Petersburg, Pa.

Filed Dec. 12, 1969, Ser. No. 20,472

Term of patent 14 years

Int. Cl. D12—10

U.S. Cl. D14—3

FIG. 1

FIG. 2

FIG. 3

FIG. 4

FIG. 1 is a side view of the camping and utility trailer showing my new design, the opposite side having substantially the same appearance;

FIG. 2 is a top view of the trailer shown in FIG. 1;

FIG. 3 is a front view of the trailer illustrated in FIGS. 1 and 2; and

FIG. 4 is a rear view of the trailer illustrated in FIGS. 1 and 2.

I claim:

The ornamental design for a camping and utility trailer, as shown.
